UNITED STATES PATENT OFFICE

WILLIAM R. McGOWEN, OF PITTSBURGH, PENNSYLVANIA, ASSIGNOR TO THE MCKAY COMPANY, OF PITTSBURGH, PENNSYLVANIA, A CORPORATION OF PENNSYLVANIA

DESIGN FOR A FOOT STOOL

Application filed April 16, 1932. Serial No. 43,516. Term of patent 14 years.

To all whom it may concern:

Be it known that I, WILLIAM R. McGOWEN, a citizen of the United States, residing at Pittsburgh, in the county of Allegheny, State of Pennsylvania, have invented a new, original, and ornamental Design for Foot Stool, of which the following is a specification, reference being had to the accompanying drawing, forming a part thereof.

I claim:

The ornamental design for a foot stool, as shown.

WILLIAM R. McGOWEN.
